W. Smith.
Wool-Drawing Mach.

No 21,988.

Patented Nov. 2, 1858.

UNITED STATES PATENT OFFICE.

WATERMAN SMITH, OF MANCHESTER, NEW HAMPSHIRE.

PREPARING WOOL AND OTHER FIBERS FOR SPINNING.

Specification of Letters Patent No. 21,988, dated November 2, 1858.

To all whom it may concern:

Be it known that I, WATERMAN SMITH, of Manchester, in the county of Hillsboro and State of New Hampshire, have invented 5 new and useful Improvements in the Process of Working Wool and other Fibrous Substances; and I do hereby declare that the same is described and represented in the following specifications and drawings.

10 To enable others skilled in the art to make and use my invention and improvement, I will proceed to describe its construction and operation referring to the drawings in which the same letters indicate like parts in 15 each of the figures.

Figure 1, is a plan of the machine. Fig. 2, is a sectional elevation.

The nature of my improvement in the process of working wool and other fibrous 20 substances consists in heating the wool or fibrous substance, to make it soft and pliable, and drawing it while hot, to straighten and elongate the fibers or sliver of the fibrous materials worked while hot.

25 In the accompanying drawings A, A, are posts connected together by the bars B, B, and girders C, C, with rails D, D, fastened to the tops of the posts A, A, and connected at one end by the bar E, the whole forming 30 a strong frame to support the other parts of the machine. The posts A, A, and the rails D, D, are perforated for the journals of the feed rollers a, a, to turn in between which rollers the sliver or slivers of wool 35 enter and pass under the roller b, over c, under d, over e, under f, over g, and between the calender rollers h, h, out of the machine, as shown in Fig. 2, of the drawing, and in the direction indicated by the arrows.

40 The journals of the rollers c, e, and g, turn in boxes on the rails D, D, and the journals of the rollers b, d, and f, turn in boxes fastened to the under side of the rails D, D, and these rails are perforated, for the journals of the 45 lower calender roller h. The journals of the upper calender roller h, turn in boxes on the top of the rails D, D. These calender rollers and the feeding rollers may be pressed together with weights or springs if 50 preferred. The feeding rollers a, a, are geared together at one end and one of their journals may be extended and a gear or pulley applied to it to operate the machine.

55 The gear F, is fastened to the lower feeding roller a, and turns the gear G, and roller b, moving its surface as fast or a little faster

than the surface of the feeding roller. The gear G, turns the gear H, and roller c, about one-sixth faster than the roller b, is turned. The gear H, has twenty-five teeth and the 60 gear I, on the opposite end of the roller c, has thirty teeth, and each of the rollers in the series has a gear of twenty five teeth at one end, by which it is turned or driven, and a gear of thirty teeth on the opposite 65 end, by which it drives the next roller in the series one-sixth faster than itself turns, except the roller g, which is the last in the series and only has the gear J, of twenty-five teeth by which it is turned, and also turns 70 the gear K, and upper calendering or delivering roller h, so as to move its surface as fast or faster than the surface of the roller g, from which it receives and draws the wool—passing through the machine. The gear K, 75 turns the gear L, and lower calendering roller h, which is the last in the series of gears.

The six large rollers are made hollow of 80 copper, brass, or some metal that will not corrode and stain the wool, and one or both of the journals to these rollers is made hollow, through which the steam is supplied to heat them from the pipe M, and branch pipes N, N, which enter the ends of the 85 journals and may be packed in the manner well known to plumbers. The water formed in these rollers, by condensing the steam which heats them, may be made to run out through the journals, by means of one or 90 more scrolls of pipe arranged inside of the rollers, in a manner well known to artificers skilled in such work.

I have described my machine with six 95 heated rollers, but it may be made with one, two, or such a number as may be preferred, and the feeding and calendering rollers may be heated also if desired.

I have described the rollers in my machine as being heated by steam which is the 100 best way known to me to heat them, but they may be heated in such other manner as may be preferred by the operator. And the difference in the motion of the rollers is described as one sixth, but it may be made 105 more or less as desired by varying the sizes of the gears.

I have worked wool on the above described machine to great advantage after it was carded, and before it is combed or gilled, 110 and by substituting it in part for gilling; but it may be used at such stages of the

manufacture as may be desirable, and in connection with carding, combing or such other machines as can be worked in connection with it.

5 By heating the wool and drawing it while hot the fibers can be drawn straighter and made longer than if they were not heated, and when drawn straight while hot and kept straight or extended until cool, by winding 10 the sliver, they will remain so during the subsequent processes of manufacture unless curled by some means. By drawing the wool so as to straighten the fibers as above mentioned the noil or short fibers are separated from the long more easily and freely, 15 and the long fibers being more perfectly straightened than they have ever been before by any process the yarn and goods made therefrom are far smoother and have a more 20 silky appearance than any goods made from wool prior to my invention, which is of the greatest utility in making worsted yarns and stuffs of every kind. After wool has been drawn on my machine it can be combed 25 faster, easier and with far more facility than before.

I contemplate that the wool or substances

drawn on this machine may be moistened by steam which may be made to issue through perforations in the cylinders or rollers, or 30 supplied by some other device. I contemplate that wool may be heated and drawn by means of a heated bar or bars, placed between a pair of feeding and delivering rollers, so that the wool may be drawn against or between the hot bars and heated while it is 35 being drawn.

I believe I have described and represented my invention so as to enable any person skilled in the art to make and use the same. 40 I will now state what I desire to secure by Letters Patent.

I claim—

In the process of drawing wool and other fibrous substances, heating the sliver of wool 45 or other substance and keeping it hot while it is being drawn by passing it over or against and in contact with heated surfaces either moving or stationary substantially as described for the purposes set forth.

WATERMAN SMITH.
